TELEGRAPH TRANSMITTING SYSTEM

Stephen Janiszewski, Chicago, Ill., assignor to
Teletype Corporation, Chicago, Ill., a corpora-
tion of Delaware

Application April 18, 1941, Serial No. 389,141

13 Claims. (Cl. 178—17)

This invention pertains to printing telegraph systems and apparatus and more particularly to transmitting distributors and control arrangements therefor.

The primary object of the invention is to provide a selector system to control transmission to a single channel of communication from a group of transmitters.

Another object is to provide a counting chain selector system for controlling the automatic and sequential transmission of messages from a plurality of tape transmitters to a single channel of communication.

Another object of the invention is to provide a telegraph system wherein a plurality of progress switches are employed for facilitating the transmission of messages to a single channel of communication automatically and sequentially from a plurality of tape transmitters.

A further object of the invention is to provide a record reader comprising means for sensing indicia in a record strip, control means, and means effective under certain predetermined conditions of operation of said sensing means to operate said control means momentarily.

To facilitate the cross office handling of messages, particularly in commercial telegraph offices, this invention provides a selector system and apparatus which will permit sequential automatic transmission of messages to a single outgoing channel of communication from individual transmitting units of a number of groups or banks of units distributed about the office. That is, one or more units of each group of units may be connected to the same outgoing line, and the selector system according to the present invention controls the sequence in which the transmission from these units takes place. The individual units may be connected either directly to an outgoing line, or to a reperforator located adjacent to a transmitter connected to an outgoing line and common to a plurality of said units. The individual transmitter unit identified with a particular channel of communication may or may not be in the same bank.

A more complete understanding of the foregoing and other objects of the present invention may be had from the following description when taken in conjunction with the accompanying drawings in which:

Fig. 1 is a perspective view of a tape transmitter employed with the system according to the present invention, parts being broken away to show other elements more clearly;

Fig. 2 is a vertical sectional view of the transmitter shown in Fig. 1 showing the manner of cooperation between the tape sensing means and the cam distributor;

Fig. 3 is a further cross-sectional view of the transmitter shown in Fig. 1;

Fig. 4 is a sectional view showing the cam means for causing the sensing pins to sense the tape periodically;

Fig. 5 is a diagram of the circuit arrangement of one form of the present invention;

Fig. 6 is a diagram of the circuit arrangement in accordance with a modified form of the present invention;

Fig. 7 is a schematic plan view of a bank of transmitters mounted on a common base and driven by a common motor; and

Fig. 8 is a schematic representation of a set of transmitting contacts.

The tape transmitter illustrated in Fig. 1, which is employed in the arrangement according to the present invention, is of the form disclosed in copending application Serial No. 345,456, filed July 15, 1940, by M. T. Goetz, to which reference may be had for a detailed description thereof. Referring to Fig. 1, the tape transmitter 11 comprises a base plate 12 on which are mounted supports 13, 14, 15, and 16 for a top plate 17. The mechanism contained between base plate 12 and top plate 17 comprises tape sensing instrumentalities and transmitting contacts with cams for their control, said control being determined by the cooperation between the sensing levers and the perforated tape. For the purposes of the present invention the tape transmitter 11 will be described briefly.

Journaled in supports 13 and 14 is a shaft 18 on which are mounted a start-stop cam 19, a series of transmitting cams 21, a tape-sensing cam 22 and a tape feeding cam 23. Cam 19 is the start-stop cam and controls the transmission of the start and the stop impulses of the start-stop permutation code signals, transmission of which the device of the present invention is adapted to control. Each of the cams 21 is provided with a notch 24 (Fig. 2), and these notches are arranged successively around shaft 18 in a helical manner such that upon rotation of the cam assembly, a corresponding series of contacts 25 are operated sequentially to effect the transmission of permutation code signals in a well-known manner.

Interposed between each cam 21 and its associated contacts 25 is a bell crank lever 26 mount-

ed freely on a shaft 27. The vertical arm of each of the levers 26 terminates in a goose-neck portion which controls the opening and closing of the associated contacts 25. The horizontal arm of each of the levers 26 is provided with a cam lug or follower 23 which cooperates with the notch 24 of its associated cam 21 to close the contacts 25 momentarily and at the proper instant in the code cycle. In blocking relation with the free end of the horizontal arm of each of the bell crank levers 26 is the depending arm of a bell crank lever 29 pivotally supported on a shaft 31 mounted in the supports 13 and 14. Each of the levers 29 tends to rotate clockwise (as viewed in Fig. 2) under the influence of its individual spring 32.

It should be noted that there is no bell crank lever 29 associated with the start-stop cam 19, and hence its associated contact 25 is invariably opened and closed for each cycle of rotation of the cam assembly on shaft 18. As is well known in start-stop telegraphy, the start-stop cam 19 is so positioned on shaft 18 that in the stop position the cam notch 24 is disposed directly over the cam follower 23 so that the contacts 25 associated therewith remain closed owing to the resiliency of the contact spring 33 of the pair of contacts 25. This condition is illustrated diagrammatically in Fig. 8, wherein the start-stop contact of the series of contacts 25 is indicated as contact 34, and since the stop condition of the transmission line is a marking condition (that is, with current on the line), contact 34 is normally closed.

As previously described, the depending arms of levers 29 act to block or permit the operation of levers 26. This blocking relation is controlled by the sensing of a perforated tape 35 by a record reader comprising a group of sensing pins 36, each of which is carried on the horizontal arm of individual bell crank levers 29. The bell crank levers 29, which will hereinafter be referred to as the tape sensing levers, are normally held in their counterclockwise position, as shown in Fig. 2, by means of a bail 37 adjustably secured to a lever 38 (Fig. 4) by a slot and screw adjustment, indicated by the numeral 39. Lever 38 carries a cam follower roller 41 which cooperates with the cam 22 so that upon each rotation of cam 22 the lever 38 is actuated against the action of a spring 42. The angular position of cam notch in cam 22 is so related to the notches 24 of the transmitting cams 21 that the bail 37 is timed to rotate clockwise, permitting springs 32 to cause the tape sensing levers 29 to bring their sensing pins 36 into contact with the tape 35 in sufficient time so that the tape may be sensed and the blocking portions of levers 29 set correspondingly to allow control of contacts 25 by the goose-neck levers 26 in accordance with the code perforated in the tape 35.

In other words, when the bail 37 is operated clockwise to permit the sensing levers 29 to sense the tape 35, those levers 29 whose pins 36 have found a perforation in the tape 35 will be rotated clockwise by their springs 32, to swing their depending arm out of blocking relation with the horizontal arm of the associated gooseneck levers 26, so that when the projections 28 thereof ride on the peripheries of their associated cams 21, and register with a notch 24, the gooseneck lever 26 associated therewith will be rotated clockwise by the action of contact spring 33, thereby permitting the associated contact 25 to close. On the other hand, if no perforation is found by the pin 36, the gooseneck lever 26 corresponding

thereto will be blocked, and no rotation of gooseneck lever 26 for closing of contact 25 identified therewith will occur.

The tape stepping cam 23 (Fig. 3) cyclically operates a tape stepping lever 43, and through a pawl 44 rotates a tape stepping ratchet 38 fixed to a shaft 40, to which is also fixed a tape feed roller 50 (Fig. 2) provided with tape feed pins 60 which cooperate with the tape feed perforations in the tape 35, to advance the tape in well-known manner.

As described in the copending application Serial No. 345,456, the shaft 18 and cams thereon are rotated through the instrumentality of a grab clutch (not shown) under the control of a clutch throw-out lever 45 which is controlled by an electromagnet 46, so that when the electromagnet 46 is energized (as will hereinafter appear) the lever 45 will be rotated clockwise against the action of its spring 47 to release the upper end of lever 45 from the driven portion of the grab clutch, thus causing rotation of the cams assembled on shaft 18. Constant rotation is imparted to the driving portion of the clutch 25 through a train of gears in each unit 11, by a motor 48 (Fig. 7). As is shown in Fig. 7, the motor 48 is common to a bank or plurality of transmitting units 11, such as shown in Fig. 1, the motor 43 and the series of transmitting units 11 being mounted on a common base member 49.

A contact 51 (Fig. 3) is provided in the energizing circuit for the magnet 46 and a mechanism, as set forth in the afore-mentioned copending application, is effective automatically when the end of the tape 35 is reached and stepped past the sensing pins 36 to open the contact 51 to suspend transmission.

The present invention provides for momentarily opening contact 51 automatically, independently of the tape-out lever 61. To achieve this result, the lever 52 (comparable to lever 104, Fig. 5, of the copending application Serial No. 345,456) is held in its clockwise position (Fig. 1) out of latching relation with arm 53 of lever 54 by a screw 55 which is adjustably positionable in a slot 56 in plate 57, the said screw 55 being adjusted to its lowermost position in slot 56 to depress the horizontal arm of lever 52 and hold it against the action of a spring 58. Thus lever 52, which normally latches with lever 53 to maintain contact 51 open when the tape has been depleted, is here shown out of the path of lever 53 in order to illustrate a feature of the present invention whereby contact 51 is momentarily opened under certain conditions as hereinafter explained.

The horizontal arm of the tape sensing levers 29 are provided with enlarged ends so that a laterally extending portion 59 (Figs. 1 and 2) at the extremity of the vertical arm of a three-armed lever 61, pivoted at 62, will cooperate only with the ends of the series of code hole sensing levers 29, and not with the special lever 63 (comparable to lever 91 of the afore-mentioned copending application). Lever 61 is also provided with an arm 64 which cooperates with a notch 24 in the No. 1 impulse cam of the series of transmitting cams 21 (Figs. 3). Lever 61 is further provided with an arm 67 terminating in a laterally disposed portion 68 adapted to overlie arm 53 of gooseneck lever 26. A spring 69 normally tends to rotate lever 61 in a clockwise direction (Fig. 2) so that the laterally disposed extremity of arm 64 constantly rides on the periphery of the No. 1 impulse cam of the series of cams 21. In this manner, lever 61, through its bail portion 59, is

adapted to sense the ends of the tape sensing levers 29 once during each revolution of cam 21, when the end of arm 64 tends to fall into notch 24. The end of arm 64 can fall fully into notch 24 only when an all-marking condition (perforations in all sensing positions in a transverse row) occurs in the tape 35, the sensing of which by pins 36 permits all levers 29 to rotate counter-clockwise under the action of their springs 32 to cause the ends of the horizontal arms of said levers 29 to clear the bail portion 59 of lever 61, whereupon lever 61 responds fully to the pull of its spring 69 so that the end 68 of arm 67 strikes against arm 53 of lever 54, causing lever 54 to rotate counter-clockwise to open its associated contact 51. Lever 61 remains in the fully selected clockwise position only for a short interval (corresponding to the transmission time of one impulse), and is restored to its initial position before the end of the same cycle in which its selection by a letters (all-marking) combination occurred. Lever 61 will remain in its counter-clockwise position until another all-marking code combination is sensed in the tape 35.

As previously mentioned, a bank or group of transmitters 11 is shown in Fig. 7 to be mounted on a common base 49 together with a motor 48. The plurality of transmitters 11 are shown connected in series for the preparation of a master tape made up of perforated messages from sections of tape inserted in separate ones of the transmitters 11 from which the signals are transmitted in sequence under the control of the inserted tape. A circuit for controlling the sequential transmission from the series of transmitters 11 is shown in Fig. 5.

The transmitter distributors are designated as 11a, 11b, and 11c, in Fig. 5, and have their start-stop contacts 34 connected in series from positive source of current over interconnecting conductors 71 and 72. The transmitting contacts of unit 11c are connected over a conductor 73 to the winding of a line control relay 74, and from thence over a conductor 75 to a set of transmitting contacts 76 located in an automatic tape feed-out unit 77. The sending contacts 76 are connected over a conductor 78 to the winding of reperforator magnets 79 and from thence to ground.

The transmitters 11a, 11b, 11c (Fig. 5) are each provided with a start or clutch magnet 46 and a pair of contacts 51 and 81, and as shown in Figs. 1 and 3, contact 51 (Fig. 3) is controlled by contact lever 54 which as described in the aforementioned copending application Serial No. 345,456 is adapted, upon absence of tape, to be held open by latch lever 52 (comparable to latch lever 104 of said copending application). As also described in said copending application, contact 81 (Fig. 1) is adapted to be held open manually, through the instrumentality of depressible member 82 and cam lug 83, to facilitate the insertion of a new strip of tape. In Fig. 5 the contacts 51 are indicated as open, and contacts 81 are shown as closed. Now, when a strip of tape is to be inserted in a transmitting unit 11, the lever 82 is depressed manually, which acts not only to unlatch the lever 52 to permit contact 51 to close, but also to hold contact 81 open while the strip of tape is being inserted.

Prior to the insertion of the tape the condition of the circuit shown in Fig. 5 is as follows: The circuit is closed from battery through contacts 34 in the units 11a, 11b, and 11c, through conductors 71 and 72, over conductor 73, through

the winding of line control relay 74, then over conductor 75, through transmitting contact 76 of the tape-out unit 77, then over conductor 78 and through the winding of reperforator magnet 79 to ground. Over this circuit, the line control relay 74 remains energized, therefore maintaining its contact 85 closed. The sequence relays 86, 87, and 88, the control relays 91, 92, and 93, and the sequence release relay 94 are de-energized since relay 95 is normally energized. The sequence start relay 95 is maintained energized by a circuit extending from positive battery, through the winding of relay 95, over conductor 96, through contact 97 of control relay 91, over conductor 98, through contact 99 of control relay 92, over conductor 101, thence through contact 102 of control relay 93, to ground. While the sequence start relay 95 is thus energized, its contacts 103 and 104 are open and its contact 105 is closed. The effect of the opening and closing of the contacts 104 and 105 upon the tape feed-out unit 77 will be described hereinafter.

Assuming that tape has been inserted in transmitter 11c of Fig. 5, both of the contacts 51 and 81 are closed, whereby a circuit will be completed from ground, through contact 51 (now closed) contact 81, thence over conductor 84 and through winding of control relay 91 to positive source of current. The energization of control relay 91 will cause its contacts 97 and 106 to open. The opening of contact 97, due to the readiness of transmitter unit 11c for transmission, will break the energizing circuit for the sequence start relay 95, which upon de-energization will close its contacts 103 and 104 and open its contact 105. The closing of contact 103 will complete an energizing circuit for sequence relay 86 from positive source of current, through contact 85 of line control relay 74, through contact 103, through the winding of sequence relay 86, then over conductor 107 and through contact 108 of sequence release relay 94 to ground. The energization of sequence relay 86 will cause the closure of its contacts 111, 112, and 113. The closure of contact 111 completes a locking circuit for the sequence relay 86 from a positive source of current, through contact 111, thence through the winding of sequence relay 86, over conductor 107 and through contact 108 to ground. Contact 112, when thus closed upon the energization of relay 86, prepares an energizing circuit for sequence relay 87 which is completed upon the closure of contact 106 as will presently appear. The closure of contact 113 completes an energizing circuit for the clutch release or trip magnet 46 of the unit 11c extending from positive source of battery, through contact 114 of sequence relay 86, over conductor 115, through contact 116 of sequence relay 87, over conductor 117, through contact 113 of relay 86, over conductor 118, thence through the winding of magnet 46 and through the closed contacts 81 and 51 to ground. The vibrating of the armature of line relay 74 will have no effect upon the sequence relay 86 since the latter relay is locked up over a circuit through its contact 111.

The transmission of signals through the tape distributor 11c will proceed until the supply of tape therein is exhausted. In the meantime, however, while such transmission proceeds, tape may be inserted in either of the units 11a or 11b, the effect of which is as follows: Assuming that tape is now inserted in unit 11b, the manually depressible lever 82 thereat will be operated to effect the closing of contacts 51 and 81 there-

in in the manner previously described in connection with unit 11c. The closure of contacts 51 and 81 of unit 11b will complete an energizing circuit for the control relay 92 from ground, through contacts 51 and 81 of unit 11b, over conductor 119, then through the winding of relay 92 to positive source of current.

Similarly, if the manually depressible lever 82 of unit 11a is operated to permit the insertion of tape therein, contacts 51 and 81 thereat will be closed to complete a circuit from ground to said contacts 51 and 81, over conductor 121, then through the winding of control relay 93 to positive battery. Transmission under the control of unit 11b will not take place until the tape in unit 11c has been exhausted, at which time the energizing circuit for the control relay 91 will be broken by the opening of contact 51 of unit 11c, through the instrumentality of the tape-out pin therein. The de-energization of control relay 91 will cause contacts 97 and 106 to close, and a circuit for the sequence relay 87 will be completed from positive battery, through contacts 112 and 106, through the winding of sequence relay 87, then over conductor 107 and through contact 108 to ground. The energization of sequence relay 87 will effect the closure of contacts 122, 123, and 124. The closing of contact 124 will complete a locking circuit for relay 87 from battery, through contact 124, winding of relay 87, conductor 107, then through contact 108 to ground. It is noted that at this time both of the sequence relays 86 and 87 are locked up. The closure of contacts 122 will cause an energizing circuit for clutch trip magnet 46 of unit 11b to be completed from positive battery, through contact 114, over conductor 115, through contact 122, over conductor 123, through the winding of clutch trip magnet 46 of unit 11b, thence through contacts 81 and 51 to ground. Transmission from the transmitting unit 11b will proceed over conductors 72 and 73 to the line relay 74, over conductor 75, through contact 76, over conductor 78, then through the reperforator magnet 79 to ground.

When the transmission from unit 11b is completed, as would be indicated by a tape-out condition, transmission will automatically begin from unit 11a because the depletion of tape in unit 11b will cause contact 51 thereat to open, thus breaking the energizing circuit for control relay 92, and causing its contact 126 to close. This completes an energizing circuit for sequence relay 88 from battery, through contacts 123 and 126, thence through the winding of sequence relay 88, over conductor 107 and through contact 108 to ground. Sequence relay 88, upon energization, will close its contacts 127, 128, and 129. The closing of contact 129 completes a locking circuit for the sequence relay 88 over conductor 107 and through contact 108 to ground.

The closing of contact 128 prepares an energizing circuit for the sequence release relay 94, which will be completed when the control relay 93 becomes de-energized in response to the depletion of tape supply in transmitting unit 11a, in which event, contact 51 therein will open, thus breaking the circuit for control relay 93. Upon the de-energization of relay 93 its contact 131 will close, thus completing a circuit for relay 94 from positive battery, through contacts 128 and 131, and through the winding of relay 94 to ground. The energization of sequence release relay 94 will cause its contact 108 to open, thereby breaking the locking circuits for the sequence

relays 86, 87, and 88. The de-energization of the control relays 91, 92, and 93 will effect the closure of their respective contacts 97, 99, and 102 to cause the energization of relay 95 over its previously described energizing circuit.

The present invention provides for the spacing out of a predetermined length of tape from the reperforator (exemplified by magnets 79) to insure the transmission of the last code combination to the signal line. This result is achieved by the tape feed-out unit 77, which is effective automatically upon tape depletion from all of the transmitting units 11a, 11b, and 11c, because when this condition arises the sequence release relay 94 is energized and the control relays 91, 92, and 93 are de-energized to cause their contacts 97, 99, and 102, respectively, to close to complete the energizing circuit for the sequence start relay 95. It is necessary to note at this point that when the relay 95 was de-energized upon the commencement of transmission from units 11a, 11b, and/or 11c, due to the opening of contacts 97, 99, and/or 102 by their respective control relays, the contact 104 was closed, and an energizing circuit for a "blank" release relay 132 was completed from positive source of current, through the winding of relay 132, through contact 133, and then through contact 104 to ground. Contact 133 is one of a pair of make before break contacts 133 and 134, and upon the energization of relay 132 its armature is attracted to close the contact 134 before the contact 133 is opened to complete a locking circuit for relay 132 from positive battery through the winding of relay 132, then through contacts 134 and 135 to ground. Contact 135 is a normally closed contact located in the tape feed-out unit and is opened by a timing device 138 and 139 of the screw and follower type. Moreover, upon the energization of relay 132, its contact 136 is also closed to prepare an operating circuit for clutch trip magnet 137, from battery, through winding of magnet 137, through contact 136 (now closed), then to ground contact 105 (now open). In this manner the tape feed-out unit 77 is prepared for operation upon cessation of transmission from units 11a, 11b, and/or 11c.

If no tape has been inserted in the transmitting units 11a, 11b, and 11c, their control relays 91, 92, and 93, respectively, remain de-energized and hence contacts 97, 99, and 102 remain closed to complete the previously traced energizing circuit for the sequence start relay 95. It is noted that the sequence start relay 95 is of the slow acting type so that at the instant that all of the control relays 91, 92, and 93 become de-energized, the energization of the sequence release relay 94 will be completed before the sequence start relay 95 pulls up its armatures. This is to allow the reperforator exemplified by magnets 79 to feed out a predetermined length of tape upon cessation of transmission. The circuit for the release relay 132 was completed and locked up so that its contact 136 was closed to prepare an energizing circuit for the clutch trip magnet 137 of the tape feed out unit 77. When the sequence start relay 95 again becomes energized it closes its contact 105 to complete the operating circuit for the clutch trip magnet 137 of the tape feed-out unit 77 from battery, through the winding of magnet 137 then through contacts 136 and 105 to ground. When this occurs, the transmitting cam shaft (which is of the type shown in Fig. 1) associated with contacts 76 is caused to rotate continuously, and the follower 138 is

caused through appropriate mechanism (not shown), to be engaged with its worm 139 and caused by said worm to travel therealong until it strikes the contact spring 140 and opens contact 135. The opening of contacts 135 breaks the energizing circuit for the magnet 132 which causes its contacts 134 and 136 to open. The opening of contacts 136 will break the energizing circuit for the clutch trip magnet 137 of the tape feed-out unit 77, thus stopping rotation of the contact cam assembly and also disengaging the follower 138 from the screw 139, and permitting contact 135 to close. However, due to the opening of contact 134, the contact 135 will have no effect upon the energization of the relay 132. The de-energization of relay 132 causes the closing of contact 133 to prepare an energizing circuit for said relay through contacts 133 and 104, contact 104 being open at this time due to the energization of the sequence start relay 95.

The feeding out of tape by the tape feed-out unit 77 may be interrupted at any time during this feed-out operation by the insertion of tape in any one of the units 11a, 11b, and 11c. The insertion of tape in said units will cause the energization of their respective control relay 91, 92, or 93 to break the energizing circuit for the sequence start relay 95 by opening any one of the contacts 97, 99, or 102. The de-energization of the sequence start relay 95 in this manner causes the closure of its contact 103 to complete a circuit for the sequence relays in the manner previously described. While the system is shown in Fig. 5 to control only three transmitter units 11a, 11b, and 11c, it is, of course, understood that the system of the present invention can be expanded to control additional transmitters by adding a sequence relay and a control relay for each transmitter.

Modification

A modified control circuit is shown in Fig. 6 and is predicated on the use of progress or step-by-step switches instead of sequence relays. In this form of the invention the tape transmitter units are indicated as 11d, 11e, and 11f, and as previously mentioned, each one of these units contains a set of transmitting contacts comprising a start-stop contact 34, a clutch trip magnet 46, and a pair of contacts 51 and 81 associated with the tape-out feature and the manually dispensible lever, respectively.

The selection of the transmitters 11d, 11e, and 11f for operation is accomplished in a predetermined sequence through the instrumentality of a two-gang progress switch 141. The signal circuits of the transmitters 11d, 11e, and 11f are connected to one section 142 of the switch 141, and the control circuits are connected to the other section 143. The progress switch 141 is provided with a shaft 144, indicated diagrammatically, which carries thereon a pair of seeker arms 145 and 146 fixed to said shaft. Section 142 of progress switch 141 is provided with a plurality of contacts 151, 152, and 153 connected to transmitter units 11d, 11e, and 11f, respectively. Moreover, section 143 is provided with a corresponding plurality of contacts 161, 162, and 163 also connected to the units 11d, 11e, and 11f, in the same order. It is, of course, understood that any predetermined number of units 11 may be employed, and a corresponding number of contacts 151-153 and 161-163 will be provided.

Progress switch 141 is operated in a step-by-

- step manner through stepping mechanism (not shown) actuated by a stepping magnet 164 under the control of a selector switch relay 165. When the relay 165 is de-energized, a circuit for magnet 164 is completed from battery, through contact 166 of relay 165, through the winding of magnet 164, thence through contact 167 of magnet 164 to ground. It is apparent that the circuit just traced constitutes a buzzer circuit for the stepping magnet 164 so long as relay 165 is de-energized, due to the making and breaking of contact 167. It is contemplated that some sort of pawl and ratchet stepping means will be associated with magnet 164 to impart rotation to shaft 144, and hence to arms 145 and 146. With no tape inserted in any of the transmitters 11d, 11e, or 11f, the relay 165 will remain de-energized to maintain the buzzer circuit for magnet 164 effective.
- Assuming that tape is inserted in transmitter 11d, the contacts 51 and 81 will be closed to prepare a circuit for energizing the relay 165, which circuit will be completed (when seeker arm 146 engages contact 161) from ground, over conductors 168 and 169, through the winding of clutch trip magnet 46 of transmitter 11d, then through contacts 51 and 81 (now closed), over conductor 171, through contact 161, over seeker arm 146, through the winding of relay 165, and through the winding of slow-to-release relay 172 (to be hereinafter referred to more specifically) to battery. Relay 165 will become energized and will attract its armature to open contact 166 to arrest the operation of the stepping mechanism.
- The energization of clutch trip magnet 46 will initiate the operation of the transmitter 11d to effect, through contacts 34 and 25, the transmission of code combinations of signaling impulses to a reperforator selector magnet 173 from ground, over conductor 168, through contacts 25 and 34 (as they are sequentially and permutably operated), then over conductor 174, through contact 151, over seeker arm 145, over conductor 175, through contact 176 of the set of "blank" sending contacts of the tape-feed-out unit 177 (hereinafter described), over conductor 178, and through the winding of magnet 173 to battery.
- In the meantime, while transmission is proceeding from transmitter 11d, tape may have been inserted in either of the transmitters 11e or 11f, or both, in which event other circuits for the energization of relay 165 will be prepared, to be completed automatically when the tape supply in transmitter 11d is exhausted, whereupon contact 51 will be opened (in the manner previously described in connection with Figs. 1 to 3) and the circuit for relay 165 will be broken, thus permitting contact 166 to close to complete again the buzzer circuit for stepping magnet 164. The stepping operation will again proceed until the seeker arm 146 of the control section or portion 143 of the progress switch 141 engages a contact 162, 163 identified with a transmitter 11e or 11f, in which tape has been inserted. Since it was assumed that tape was inserted in transmitter-unit 11e (which caused contact 51 to close), an energizing circuit for relay 165 will be completed from ground, over conductors 168, 182, and 179, through the winding of clutch trip magnet 46 of transmitter 11e, through contacts 51 and 81 (now closed), over conductor 181, through contact 162, over seeker arm 146 (now positioned thereat), through the windings of relays 165 and 172 to battery. The buzzer circuit for stepping magnet 164 will thereupon be held open, and the

seeker arm 146 will remain at contact 162 so long as there is tape in transmitter 11e. Transmission will thereupon ensue under the control of the tape in unit 11e, from ground, over conductors 168 and 182, through contacts 25 and 34, over conductor 183, through contact 152, over seeker arm 145 (now engaging contact 152), over conductor 175, through contact 176, over conductor 178, and through the winding of reperforator selector magnet 173 to battery.

When the tape has become exhausted in transmitter 11e, the progress switch 141 will be caused to operate, as previously described, to step the seeker arms 145 and 146 around in search for a contact 151—153 and 161—163 associated with a prepared transmitting circuit. If tape has been inserted in transmitter 11f, then the progress switch will stop at contacts 153 and 163, to effect transmission thereat. If tape has not been inserted in transmitter 11f, but has again been inserted in transmitter 11d, then the progress switch 141 will continue to advance the seeker arms 145 and 146 until a prepared circuit is found, which in this instance would be contacts 151 and 161.

Now, in the event that tape has not been inserted in any of the transmitters 11d, 11e, and 11f, means is provided for automatically feeding out a predetermined length of tape from the reperforator (exemplified by magnet 173), to insure that the last code combination perforated by the reperforator will be retransmitted. To achieve this result, the tape feed-out unit 177 is provided, which is operative under the control of the feed-out relay 172. Relay 172 is of the slow-release type and normally remains energized during transmission from units 11d, 11e, and 11f. However, if the progress switch 141 passes through three or more idle transmitter positions, the feed-out relay 172 will release (as shown) and close its contact 184. A relay 185 controls the effectiveness of the tape feed-out unit 177, and is deenergized while the transmitters 11d, 11e, and 11f are idle, and the predetermined length of tape has been fed out of the unit 177, as will presently appear.

When tape is inserted in any of the transmitters 11d, 11e, and 11f, and the progress switch 141 stops at a contact 161—163 associated with a "ready" transmitter, an energizing circuit will be completed for relays 165 and 172, as previously described, and the relays 165 and 172 will become energized. The energization of relay 165 acts to break the buzzer circuit for the stepping magnet 164 of the progress switch 141. At the same time, the energization of relay 172 causes armature 186 to swing from contact 184 to contact 187. The closing of contact 187 completes an energizing circuit for relay 185, from ground through armature 186, contacts 187 and 188, and winding of relay 185 to battery. The energization of relay 185 causes armatures 189 and 191 to be attracted to close contacts 192 and 193, and to open contact 188. The relay 185 becomes locked up over a locking circuit extending from battery, through the winding of relay 185, through contact 193, over armature 191 and conductor 194, and through contact 195 to ground. Contact 195 is normally closed, and is momentarily opened, as will presently appear, by a follower arm 196 cooperating with a worm 197 of a screw and follower timing device.

The closing of contact 192 prepares an energizing circuit for a clutch trip magnet 198 of the tape feed-out unit 177. So long as transmission

is ensuing from transmitters 11d, 11e, and 11f, this condition of the relays 172 and 185, and the feed-out unit 177 persists. However, if transmission ceases, due to the depletion of tape in the transmitters 11d, 11e, and 11f, the energizing circuit for relays 165 and 172 will be opened. The relay 172 is slow-to-release and hence, after the cessation of transmission for a predetermined interval, the de-energization thereof permits its armature 186 to open contact 187 and to close contact 184, to complete an energizing circuit for the clutch trip magnet 198, extending from ground, through armature 186, contact 184, armature 189, contact 192 (now closed), over conductor 190, and through the winding of magnet 198 to battery. Upon the energization of magnet 198, a transmitting cam mechanism (not shown, but similar to that shown in Fig. 1) is initiated into operation to effect the continuous cyclical operation of contacts 176 and 201, to transmit to the reperforator magnet 173 a plurality of "blank" code combinations of impulses. The number of "blank" code combinations so transmitted is predetermined by the cooperation of follower 196 and screw 197. Upon energization of magnet 198 the follower 196 is caused (through instrumentalities not shown) to engage the screw 197 which is constantly rotating. The follower 196 travels along screw 197 until it strikes arm 202 of contact 195, thereby causing contact 195 to open to break the locking circuit for relay 185 (it being remembered that contact 193 is at this time closed and contact 188 is open). The deenergization of relay 185 causes armatures 189 and 191 to be released to open contacts 192 and 193 and permit contact 188 to close. The opening of contact 192 breaks the energizing circuit for magnet 198, which arrests the transmitting cam distributor associated with contacts 176 and 201, and also lifts follower 196 out of engagement with screw 197, permitting the follower 196 to return to its initial position, and the contact 195 to close.

In this condition of the apparatus, the relays 45 165, 172, and 185 will remain de-energized, and the progress switch 141 will continue to operate, until tape is again inserted into one or more of the transmitters 11d, 11e, or 11f. Upon the insertion of tape in any of said transmitters, the 50 relays 165 and 172 will become energized when arm 146 engages one of the contacts 161—163 associated with a transmitter in the "ready" position. The energization of 165 causes the 55 buzzer circuit for magnet 164 to be disabled, and the energization of relay 172 causes armature 186 to be attracted to close contact 187 and to open contact 184. This action of relay 172 conditions the tape feed-out unit for subsequent 60 automatic tape feed-out operation by completing the energizing circuit for relay 185, which becomes locked-up over the afore-mentioned locking circuit through contact 195. The circuits 65 associated with the tape feed-out unit 177 will thus remain prepared until, upon cessation of transmission from all the transmitters 11d, 11e, and 11f, the relay 172 is again de-energized, thereby completing, through contacts 184 and 192, the energizing circuit for the clutch trip magnet 198 of the tape feed-out unit 177. While 70 the system shown in Fig. 6 controls only three tape transmitters, it is understood that this system could be expanded to control additional transmitter units by utilizing additional segments on the progress switch 141.

75 Although the present invention has been dis-

closed in connection with certain specific embodiments thereof, it is understood that such embodiments are merely illustrative and not restrictive, and that all forms coming within the scope of equivalency of the appended claims are intended to be covered by the invention.

What is claimed is:

1. In a tape transmitter, a plurality of contacts, a corresponding plurality of contact operating levers, a series of cams for controlling the operation of said levers successively, a series of tape sensing levers, each of said levers having an arm for blocking, under certain operating conditions, said contact levers against operation, a control means, and an instrumentality co-operating with said sensing levers for actuating, in response to a certain setting of said sensing levers, said control means momentarily.

2. In a record reader, means for sensing indicia in a record strip, control means, cyclically rotatable cam means, a multiple armed lever comprising one arm cooperable with said sensing means, one arm cooperable with said cam means and one arm cooperable with said control means, and means effective under certain predetermined conditions of operation of said sensing means to operate through the cooperation of said arms said control means momentarily.

3. In a telegraph system, a plurality of tape transmitters, a tape controlled contact in each transmitter, a channel of communication, a starting circuit, a signal controlled relay connected in said channel to control the effectiveness of said starting circuit, said circuit comprising a counting chain selector system having a control relay individual to each transmitter and rendered operative by the closing of its associated tape controlled contact, a sequence relay associated with each control relay, means controlled by said sequence relays to govern the sequential operation of said tape transmitters, a sequence start relay, and means governed by each of said control relays for controlling the operation of said sequence start relay whereby said signal controlled relay initiates the counting chain selector system for facilitating under the control of said first recited means the automatic and sequential transmission of messages from said transmitters to said channel of communication.

4. In a telegraph system, a plurality of tape transmitters, a single channel of communication, means including a counting chain selector system for facilitating automatic and sequential transmission of messages from said transmitters to said channel of communication, and means effective automatically in response to tape depletion in all said transmitters to insure the completion of transmission of messages to said channel of communication.

5. In a telegraph system, a plurality of tape transmitters, a single channel of communication, means including a plurality of progress switches for facilitating automatic and sequential transmission of messages from said transmitters to said channel of communication, and means effective automatically in response to tape depletion in all said transmitters to insure the completion of transmission of messages to said channel of communication.

6. In a telegraph system, a plurality of message tape transmitters, a blank transmitter, a signal storage device operated by signals from each of said transmitters for preparing a record

tape, a master transmitter for receiving tape from said signal storage device for retransmission of messages, and means responsive to tape depletion in all of said message tape transmitters to feed tape from said tape signal storage device to said master transmitter.

7. In a telegraph system, a plurality of tape transmitters, an auxiliary tape feeding means, a single channel of communication, and means responsive to the depletion of tape in all of said transmitters to operate said auxiliary tape feeding means to insure the completion of transmission of a message to said channel of communication.

8. In a telegraph system, a plurality of tape transmitters, an auxiliary tape feeding means, a single channel of communication, means to sequentially operate said transmitters, means controlled by the depletion of tape in all of said transmitters to effect the operation of said auxiliary tape feeding means to insure the completion of transmission of a message to said channel of communication.

9. In a telegraph system, a plurality of transmitters, a single channel of communication, transmitting circuits for each of said transmitters, control circuits for each of said transmitters, means including a counting chain selector system for sequentially operating said transmitters, means associated with said counting chain selector system to respond to a closed condition of one of said transmitting circuits to initiate transmission, and means operable by tape depletion during transmission to effect the control of the first mentioned control circuit to cease transmission of the particular unit transmitting.

10. In a telegraph system, a plurality of transmitters, a single channel of communication, transmitting circuits for each of said transmitters, control circuits for each of said transmitters, a plurality of rotary stepping switches, a circuit for controlling rotation of said stepping switches, said stepping switches being rotatable to close a transmitting circuit to operate its first mentioned control circuit to initiate transmission to said single channel of communication, means operable by the selection of said closed transmitting circuit to operate the controlling circuit of said stepping switches to stop rotation of said stepping switches during transmission, and means responsive to the depletion of tape during transmission to control said first mentioned control circuit to stop transmission and to operate the controlling circuit of said stepping switches to permit rotation of said stepping switches.

11. In a telegraph system, a plurality of message tape transmitters, a blank tape transmitter, a single channel of communication, transmitting circuits for each of said message tape transmitters, control circuits for each of said message tape transmitters, means including a counting chain selector system for sequentially operating said transmitters, means associated with said counting chain selector system to respond to a closed condition of one of said transmitting circuits to initiate transmission, means operable by tape depletion during transmission to effect the control of the first mentioned controlling circuit to stop transmission of the particular unit transmitting, and means responsive to the depletion of tape in all of said transmitters to operate said blank tape transmitter to insure the completion of the messages to said channel of communication.

12. In a telegraph system, a plurality of message tape transmitters, a blank tape transmitter, a single channel of communication, transmitting circuits for each of said transmitters, control circuits for each of said transmitters, a plurality of rotary stepping switches, a circuit for controlling rotation of said stepping switches, said stepping switches being rotatable to select a closed transmitting circuit to operate its first mentioned control circuit to initiate tape transmission to said single channel of communication, means operable by the selection of said closed transmitting circuit to operate the control circuit of said stepping switches to stop rotation of said stepping switches during transmission, and means responsive to the depletion of tape during transmission to control said first mentioned control circuit to stop transmission of the particular unit transmitting, and to operate the controlling circuit of said stepping

switches to permit rotation of said stepping switches, and means responsive to tape depletion in all of said message tape transmitters to effect the operation of said blank tape transmitter to thereby insure the transmission of a complete message to said single channel of communication.

5 13. In a telegraph system, a plurality of message tape transmitters, a blank tape transmitter, a reperforator operated by signals from each of 10 said transmitters for preparing a record tape, a master transmitter for receiving tape from said reperforator for transmission, and means responsive to tape depletion in all of said message tape transmitters for operating said blank tape transmitters to feed tape from said reperforator to said master transmitter to insure the transmission of a complete message by said master transmitter.

STEPHEN JANISZEWSKI.
